UNITED STATES PATENT OFFICE.

ORLEY A. BIRD, OF CENTERBURG, OHIO.

RAILWAY-SWITCH.

No. 851,913.

Specification of Letters Patent.

Patented April 30, 1907.

Application filed January 16, 1907. Serial No. 352,559.

To all whom it may concern:

Be it known that I, ORLEY A. BIRD, a citizen of the United States, residing at Centerburg, in the county of Knox and State of Ohio, have invented certain new and useful Improvements in Railway-Switches, of which the following is a specification.

My invention relates to railway switches and particularly to that class of switches used upon street railways and located at street corners.

The object of the invention is to provide a switch of this character that may be controlled by the motorman from the car.

15 A further object of the invention is the provision of a switch of this character that may be controlled by the motorman from the car and constructed in such manner that the switch may be left open for following cars or 20 closed by the motorman as desired.

A further object of the invention is the provision of a switch of the character set forth 25 constructed in such manner that all of the parts thereof may be located beneath the surface of the road-bed and consequently out of 30 the path of vehicle wheels and the like.

Further objects and advantages of the invention will be set forth in the detailed description which now follows.

35 In the accompanying drawing: Figure 1 is a vertical section through the road-bed and through portions of a car, Fig. 2 is a plan view of the track and of the switch operating members illustrating a casing which incloses 40 said members, in section, Fig. 3 is a transverse vertical section upon line $x-x$ of Fig. 2, Fig. 4 is a partial longitudinal section upon line $y-y$ of Fig. 2, Fig. 5 is a rear end elevation of the car, illustrating a switch closing 45 yoke hereinafter described, and, Fig. 6 is a plan view of the truck frame illustrating a 50 rocking bar hereinafter described.

Like numerals designate corresponding parts in all of the figures of the drawing.

55 The numeral 5 (see Figs. 1 and 2) designates a grooved plate, the side wall of which is cut through as at 6 for the reception of a tongue 7 of a lever 8. This lever 8 is pivoted as at 9 in a casing 10 and is secured at its outer end 50 to the end of a rod 11. This rod passes through a casing 12 and has an elongated slotted portion 13 at its opposite end. A pin 14 which is carried by a rocking lever 15 engages this elongated slotted portion of the 55 rod 11. The rocking lever 15 is pivoted as at 16 in a casing 17. A link 18 connects the op-

posite end of this rocking lever with a switch tongue 19, said switch tongue being normally forced toward the right in Fig. 3 by a spring 20. A second link 21 connects the 60 rock lever 15 with a switch closing lever 22 which is pivoted as at 23 in a slotted plate 24. By referring to Fig. 4, it will be seen that the link 21 is pivoted as at 25 to the switch throwing lever in such manner that its pivot point 65 is below the pivot point 23, by virtue of which the switch throwing lever 22 may be thrown to the dotted line position illustrated at 26 in Fig. 4 when the lever 15 is rocked. Carried upon the front truck 27 of the car is 70 a rocking bar 28. This rocking bar carries a rearwardly extending hooked rod 29, the hooked end 30 of which is adapted when depressed, to engage the tongue 7 of the lever 8. An upwardly extending arm 30 which is connected to the rocking bar 28 is connected by 75 a rod 31 with a bell crank lever 32. This bell crank lever is pivoted as at 33 and is adapted to be depressed by a foot-piece 24 which projects into the motorman's vesti- 80 bule. A spring 35 normally tends to hold the hooked rod 29 in an elevated position.

A yoke 36 (see Figs. 1 and 5, is pivoted between the side members of the rear truck 37. A spring 38 normally holds this yoke 85 in an elevated position. An arm 39 of the yoke is connected by a rod 40 with a bell crank lever 41 which is pivoted at 42. A second foot plunger 43 is adapted to actuate the bell crank lever to throw the cross por- 90 tion 36 of the yoke downwardly.

The operation of the device is as follows: When the car is moving in the direction of the arrow in Fig. 1, if it be desired to throw the switch to direct the car on to the side 95 track, the motorman presses upon the foot piece 34. He presses the left end of the bell crank 32 downwardly against the tension of the spring 35. This in turn throws the hooked end 30 of the rod 29 down into such 100 position that it rides through the grooved portion of the plate 5 and engages the tongue 7, throwing said tongue to the dotted line position shown in Fig. 2. This in turn, rocks the lever 15 upon its pivot 16 and brings said 105 lever and the link 18 into alinement with each other, thereby moving the switch tongue 19 over to the dotted line position illustrated in Fig. 2. It will be apparent that when the link 18 and the lever 15 are in direct alinement with each other, it will be impossible 110 for the switch tongue to be moved over acci-

- dentally, for these parts are then on a dead center with relation to each other. When the rocking lever 15 is rocked in the manner just described, the switch closing lever 22 is thrown upwardly by the link 21 to the dotted line position illustrated in Fig. 4. If the car following is also to be directed upon the side track, the motorman permits the car to pass on without actuating the yoke 36, but if the car following is to proceed along the main track, the motorman depresses the foot-piece 43, rocking the bell crank lever 41 upon its pivot and throwing the cross portion of the yoke 36 downwardly, thereby bringing the yoke into such position that it will strike the switch closing lever 22 and throwing said lever back to the full line position illustrated in Fig. 4, thereby returning the switch parts to the position illustrated in Fig. 2.
- It will be noted that the switch engaging rod 29 is carried upon the truck instead of being carried by the car body. By virtue of this construction said rod is always held in proper alignment with the grooved plate.
- It will also be noted that the yoke 36 is carried upon the truck and is consequently held in proper position to engage the switch closing lever.
- From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.
- What I claim, is:
1. In a switch operating mechanism, the combination with the truck of a car, of a

rocking bar journaled in said truck, manually operable members controllable from the motorman's station adapted to rock said bar, a switch throwing hook carried by said bar, a grooved plate, a lever projecting into the grooved portion of said plate and adapted to be engaged by said hook throwing bar, a switch tongue, connections between said lever and said switch tongue, a switch closing member adapted to be thrown up above the road-bed when said lever is actuated, and a manually operable member carried by the car and adapted to strike said switch closing member.

2. In a device of the character described, the combination with a switch tongue, of a rocking lever, a link connection between the switch tongue and said rocking lever, a switch closing lever, a link connection between said switch closing lever and said rocking lever, a switch closing hook carried by a car, a lever adapted to be engaged by said switch closing hook, and a connecting member between the last named member and the rocking member.

3. In a device of the character described, the combination with a switch tongue, of mechanism connected to said switch tongue and adapted to be actuated from a car, a switch closing lever adapted to be elevated when said mechanism is actuated, a yoke carried by the rear truck of the car, and manually operable means for depressing a portion of said yoke, said yoke being adapted to engage and depress the switch closing member.

In testimony whereof I affix my signature in presence of two witnesses.

ORLEY A. BIRD.
